UNITED STATES PATENT OFFICE.

FRANK WOODBRIDGE, OF INDIANAPOLIS, INDIANA.

COLOR-CHANGING DISPLAY APPARATUS.

SPECIFICATION forming part of Letters Patent No. 743,129, dated November 3, 1903.

Original application filed April 7, 1902, Serial No. 101,622. Divided and this application filed September 19, 1902. Serial No. 123,994. (No model.)

To all whom it may concern:

Be it known that I, FRANK WOODBRIDGE, a citizen of the United States, residing at Indianapolis, in the county of Marion and State 5 of Indiana, have invented certain new and useful Improvements in Color-Changing Display Apparatus, of which the following is a specification.

A color-changing apparatus consisting of 10 two or more superimposed disks or segments the front ones of which are perforated or cut, so as to expose portions of the rear ones to view, and the faces of which are variously colored is a well-known device. So far as I 15 am aware a change of color effect in such apparatus has been produced by a sudden reversal of direction of movement of the device and consequent relative shifting of the color-carrying members.

20 The object of my present invention is to provide a color changing or exhibiting apparatus in which one or more of the color members are connected to and disconnected from the driving means, so that though the direction of movement be unchanged one or more of the color members may be allowed to attain a speed different from that of the others, thus 25 changing the relative positions of the color members, and consequently changing the 30 color effect produced thereby.

The accompanying drawings illustrate my invention as applied to a two-member or two-disk device especially designed for use in connection with my card-displaying apparatus 35 described and claimed in my pending application Serial No. 101,622 and of which this application is a division.

Figure 1 is a side elevation; Fig. 2, an axial sectional detail; Fig. 3, a section on line 3-3 of 40 Fig. 2; and Figs. 4 and 5 elevations, on a smaller scale, of desirable forms of coöperating color members or disks.

In the drawings, 10 indicates a main shaft, which in the drawings is shown as the armature-shaft of a small electric motor 11. Secured to the end of shaft 10 is a head 12, to the outer end of which is secured a color-disk 13, having one or more segmental openings 13' 13," &c. Freely rotatable upon head 12 45 50 back of disk 13 is a sleeve 14, to which is secured a disk 15, the face of which is section-

ally colored, as indicated in Fig. 4. Sleeve 14 carries at its inner end a flange 16, having teeth 17, which are adapted to be engaged by a pawl 18, pivoted upon a lug 19, carried by sleeve 14. Pawl 18 is beveled at its free end, which projects beyond flange 16, and is normally urged into engagement with teeth 17 by any suitable means, such as a spring 18'. That portion of pawl 18 which engages teeth 17 is preferably V-shaped in cross-section in order that when it is first released, so as to be forced into engagement with teeth 17, said teeth may not be immediately caught thereby, as a sudden and positive engagement 65 might result in a distortion or breaking of the teeth or lever.

Surrounding sleeve 14 is a collar 20, one end of which is beveled, as at 21, to engage the free beveled end of pawl 18 and when the 70 collar is shifted to swing said pawl out of engagement with teeth 17. Collar 20 carries a spring-brake 20', which may be brought into engagement with flange 16 and serve to further retard disk 15 when pawl 18 is disconnected from teeth 17. Collar 20 may be intermittently shifted by any suitable means. In the drawings I have shown the collar as supported by a bracket 22, carried by a rod 23, normally urged by a spring 24, so as to 80 keep collar 20 out of engagement with pawl 18. Rod 23 carries a bracket or arm 25, the end of which is a cam 26, which lies in position to be engaged by any one of a number of pins 27, carried by a wheel or gear 28. 85 Gear 28 may be driven in any suitable manner, as by a worm 29, carried by shaft 10.

In operation pawl 18 is normally in engagement with teeth 17, so as to positively connect with two disks 13 and 15. The disks 90 are therefore positively rotated by shaft 10, and a certain color effect is produced. As gear 28 revolves pins 27 come into engagement with cam 26, and thereby force collar 20 into engagement with pawl 18, so as to withdraw the pawl from engagement with teeth 17 and at the same time bring the brake-spring into engagement with flange 16. As a consequence disk 15 will lag behind disk 13. As soon as pin 27 passes cam 26 collar 20 is withdrawn 95 and pawl 18 drops into engagement with the teeth 17. Owing to the triangular shape of

the pawl it does not immediately partially engage the toothed flange, but slips over the teeth, so as to bring disk 15 gradually up to the constant speed of disk 13, in this manner avoiding the possibility of breaking the teeth or pawl, which would result unless there were some means for gradually overcoming the inertia of the disk 15. The release and return of pawl 18 causes a shifting of disk 15 with relation to disk 13 so that different portions of its colored sections will be exposed through the openings 13' 13'', &c., thus causing a change in the resultant color effect produced by the rotation of the two disks.

15 I claim as my invention—

1. In a color-changing display apparatus, the combination, with a pair of superimposed colored disks, portions of one of which are visible through portions of the other, of means for rotating one of said disks constantly in one direction, a separable positive connection between said disks, and means for intermittently separating and reconnecting said connection during rotation of the disks.

2. In a display apparatus, the combination with a pair of sectionally-colored disks one revolute upon the other and portions of one of which are visible through portions of the other, a toothed flange carried by one disk, a pawl carried by the other disk and having a wedge-shaped face adapted to lie between any two of the teeth of the toothed flange so as to connect the two disks in the manner described, means for rotating one disk, and means for intermittently withdrawing the pawl from engagement with the toothed flange.

3. In a display apparatus, the combination with a pair of sectionally-colored disks one revolute upon the other and portions of one of which are visible through portions of the other, a toothed flange carried by one disk, a pawl 18 carried by the other disk and adapted to engage the toothed flange substantially in the manner described, means for rotating one disk, and means for intermittently withdrawing the pawl from engagement with the toothed flange.

4. In a display apparatus, the combination with a pair of sectionally-colored disks one

revolute upon the other and portions of one visible through portions of the other, a toothed flange carried by one disk, a pawl carried by the other disk and adapted to engage the toothed flange, means for rotating one disk, 55 a collar, a brake carried by said collar, and means for intermittently shifting the collar so as to engage the pawl and withdraw it from the toothed-flange end so as to bring the brake into engagement with said flange. 60

5. In a color-changing display apparatus, the combination, with a pair of superimposed disks the under one of which is varicolored and the upper one of which has portions which are black and other portions through 65 the under disk may be seen, of means for rotating one of said disks constantly in one direction, a separable positive connection between said disks, and means for intermittently disconnecting and reconnecting said 70 connection during rotation of the disks whereby said other disk may be caused to rotate with the first disk or may momentarily lag behind said first disk so that the relation of said other disk to the first disk may be shifted 75 to produce a different resultant color.

6. In a color-changing display apparatus, the combination, with a pair of superimposed colored disks, portions of one of which are visible through portions of the other, of 80 means for rotating one of said disks continuously in one direction, a separable connection between the disks, said connection being such as to gradually positively connect the two disks whereby the loose disk may be gradually positively connected with the continuously-rotating disk but such that, when connected, the relative positions of the two disks cannot be changed except by positive disconnection of the connecting means, and 85 means for intermittently separating and reconnecting said connection during rotation of the disks.

In witness whereof I have hereunto set my hand and seal, at Indianapolis, Indiana, this 95 10th day of September, A. D. 1902.

FRANK WOODBRIDGE. [L. S.]
